UNITED STATES PATENT OFFICE.

JOHN BOWEY, JR., OF LONDON, ONTARIO, CANADA

GAS-PRODUCER.

No. 888,780.

Specification of Letters Patent.

Patented May 26, 1908.

Application filed June 20, 1907. Serial No. 379,967.

To all whom it may concern:

Be it known that I, JOHN BOWEY, Jr., of the city of London, in the Province of Ontario, Canada, have invented certain new and useful Improvements in Gas-Producers, of which the following is a specification.

My object is to devise a gas producer which will be as nearly automatic in its action as possible particularly in its feeding, 10 its stirring and the elimination of ashes, thus tending to produce a richer and more uniform gas, with a decrease in the cost of operation. The stirrers are given a rotary movement in the fuel, and simultaneously there- 15 with a vertical reciprocating movement to alternately project them into the heated zone in the fuel and withdraw them to cool. As the stirrers are withdrawn a fresh charge of fuel is automatically fed to the producer, 20 and before the stirrers commence their downward movement a fresh charge is automatically admitted to the feeder. The ashes are eliminated through an automatically rocked grate into a movable receptacle forming 25 a water seal for the grate and producer.

Figure 1 is a vertical elevation, partly broken away, of my improved producer. Fig. 2 is a plan view of the producer. Fig. 3 is an enlarged plan view of the feeding 30 apparatus. Fig. 4 is a side elevation of the same partly in section. Fig. 5 is a sectional plan view of the producer showing the grate. Fig. 6 is an elevation partly in section of the 35 lower part of the producer showing the grate. Fig. 7 is a detail of the worm gearing between the grate driving shaft and its driving shaft.

In the drawings like letters of reference indicate corresponding parts in the different 40 figures.

1 is the generator of the producer, of which 2 is the gas exit pipe. The producer is provided with an automatic feed, automatic stirring means, and automatic ash 45 ejecting means, the various mechanisms being simultaneously driven and synchronized.

As the operation of the feed is controlled from the stirring mechanism I will first 50 describe this latter. On the top of the producer are secured a plurality of vertical guide rods 3. On these guide rods slides a frame 4. In this frame are journaled spindles 5, on the lower end of each of which is secured an arm 6. Each of these arms is 55 loosely pivoted to the upper end of one of the poker-shaped stirrers 7. These stirrers

extend down into the generator through the balls 8 in which they are slidable. These balls are set in the sockets 9, in which they are free to rock in any direction. It is 60 evident that by rotating the spindles 5 the stirrers may be rotated in closed curves inside the generator. Also, as the frame 4 is vertically movable, the stirrers may be alternately projected downward into the 65 heated zone of fuel and withdrawn therefrom to cool.

The arms are rotated and the frame reciprocated by the mechanism I will now describe.

Secured to the upper end of each spindle 5 is a gear wheel 10. These gear wheels mesh with the gear wheel 11, (Fig. 2), which is centrally threaded to work on the vertical threaded shaft 12 secured to the top of the 75 generator. With this gear wheel 11 meshes a pinion 13 sliding by means of a feather key and key-way on the shaft 14 passing slidably through a bearing on the frame 4 and journaled in the frame 15 connecting the 80 upper ends of the guide rods 3. By rotating this shaft it is evident that the gear wheels 10 and 11 will be rotated and a rotary movement thus imparted to the stirrers, and a reciprocating movement also through the 85 medium of the reciprocation of the frame 4 due to the screwing up and down on the shaft 12 of the gear wheel 11. To give this reciprocation it is necessary to rotate the shaft 14 alternately in opposite directions. 90 For this purpose I provide the driving shaft 16 journaled upon the top of the generator, and provided with the usual driving pulley 16'. This shaft carries a sleeve 17 (Fig. 1) to which is secured the bevel pinions 18 and 19. 95 The sleeve will of course be longitudinally movable on the driving shaft with a feather key and key-way in the ordinary manner well known in connection with such reversing gear. By shifting the sleeve on the driving shaft either pinion may be brought into mesh with the bevel gear wheel 20 fast on the lower end of the shaft 16. For the purpose of shifting this sleeve I provide a hydraulic or steam cylinder 21, the piston of which is 100 connected with the sleeve. A suitable valve 22 is provided for admitting the operating fluid to either end of the cylinder. To the stem of this valve is connected a connecting rod 23. The other end of the connecting 105 rod is pivoted on one arm of the bell-crank lever 24, fulcrumed on a suitable part of the

frame of the apparatus. The other arm of this bell-crank lever is pivotally connected to the lower end of the shifter rod 25, the upper end of which is slidable through the frame 15. Two trip arms 26 are secured to the shifter rod, one above and one below the frame 4. From this construction it follows that when the frame 4 contacts with the upper trip arm 26 the shifter rod is operated to move the valve 22 to cause the cylinder to reverse the position of the bevel pinions 18 and 19, thus causing a reversal of the movement of the frame 4. A similar shift is made when the frame 4 contacts with the lower trip arm 26, and thus the stirrers are rotated and reciprocated constantly as long as power is applied to the driving shaft 16. This reciprocation of the stirrers is very important as it enables me to dispense with water cooling, and also, owing to the varying paths followed by the ends of the stirrer rods in the fuel, the latter is more thoroughly agitated.

The feeding device comprises a feed tube or hopper 27 provided with closures 28 and 29. The upper closure 28 is formed as a slide movable transversely of the hopper in guides 30. The lower closure is formed as a swinging gate 29 hinged at one side of the lower end of the feed hopper. This gate is normally held closed by a counter-balancing weight 31 fast on the arm 32, secured to one end of the spindle 33, journaled in the feed hopper. (See Figs. 3 and 4.)

Within the hopper an arm 34 is secured to the spindle and is pivotally connected to one end of the connecting rod 35, the lower end of which is pivotally connected with the upper side of the gate.

The slide 28 is normally held closed by means of the counter-balancing weight 36, secured to an arm 37, which is secured on one end of the spindle 38, journaled in bearings carried on the ends of the guides 30.

An arm 39 secured to the spindle 38 extends down through a clevis 40 on the end of the slide 28. This clevis is preferably provided with a friction roller at each end to ease friction between it and the arm 39. An operating arm 41 is also secured to the spindle 38. An operating arm 42 is secured to the spindle 33. The operating arm 42 is in the path of the trip arm 43, which is secured to and forms part of the frame 4. The operating arm 41 is adapted to be engaged by the bent end of the shifter rod 44, which is slid able in the frame 15 and carries a finger 45, which projects into the path of a trip-arm 46, secured to or forming part of the frame 4. From this construction it follows that when the frame 4 reaches nearly its highest predetermined position the trip arm 46 will engage the finger 45 and lift the shifter rod 44, which, through the connections already described, withdraws the slide 28, allowing the fuel to run through the hopper and fill the

lower part of it. When the frame descends the counter-balancing weight 36 moves the slide to close it and cut off the lower portion of the hopper from the upper.

When the frame 4 reaches the lower predetermined limit of its movement the operating arm 42 is engaged by the trip arm 43 and the gate 29 opened to feed the charge of fuel between the gate and the slide into the generator. This feed, it will be seen, takes place at the moment the stirrers are about to begin their upward movement of withdrawal from the fuel, as this is the time at which the stirring is not so necessary as it is after the fresh charge has become heated to incandescence and ash begins to form.

The ash ejecting mechanism is operated simultaneously with the operation of the stirring and feed mechanisms, but is provided with means whereby the rate of ejection can be varied as desired. The ejecting means I preferably employ are shown in Figs. 5 and 6. A series of grate bars 47 are suitably journaled in the frame 48 of the grate, and each one is provided at its end outside this frame with an arm 49. The arms are all pivotally connected to a rock bar 50. A connecting rod 51 is pivotally connected to this rock bar and to a crank disk 52, secured to the shaft 53 suitably journaled outside the generator. The connection between the connecting rod and the crank disk is preferably by means of a wrist pin 54, adjustable to and from the center of the crank in any of the well known ways commonly employed. The shaft 53 is provided with a worm wheel 55 which meshes with a worm 56 secured to the lower end of the shaft 57, suitably journaled on the generator, and geared by means of bevel gearing 58 with the main driving shaft 16. Thus the grate bars are continuously rocked as long as the driving shaft is in motion, and as the rate of ejection of the ashes depends on the extent of the rocking movement of the bars, and as the extent of this movement may be adjusted by adjusting the wrist pin 54, it will be seen that the rate of ejection of the ashes may be easily varied independent of the rate of movement of the main driving shaft.

The grate is sealed by means of a receptacle 59, which is laterally movable from beneath the generator preferably by being provided with wheels 60 running on the track 61 which extends from beneath the generator to any desired point outside. This receptacle is filled with water to form the water seal, and also serves to receive the ejected ashes. In order that it may pass the frame 48 it is necessary to provide means for reducing the height of one end. For this purpose one end is divided and the upper part 62 hinged upon the lower part. Thus this end may be swung down to the position shown in dotted lines in Fig. 6 when it is desired to

remove the receptacle from beneath the generator. A water pipe 63 is preferably provided extending to a point over the normal position of the receptacle, and through which 5 the latter may be supplied with water if necessary.

64 is a blast pipe through which the air supply is forced into the generator. In the gas exit pipe 2 I show a belt driven fan 65 10 which may be used to induce a slight suction in the gas exit pipe.

From the above description it will be seen that I have devised a gas producer in which the operation of introducing fuel, stirring the 15 fuel, and ejecting the ashes are all automatically performed, and in which the rate of ejection of the ashes may be varied as desired to suit the amount or quality of fuel being employed. It will also be seen that 20 the necessity for water cooling the stirrers is avoided and the stirring more efficiently performed than with the stirrers now commonly employed.

What I claim as my invention is:—

25 1. In a gas producer the combination of an automatically operated stirrer; automatic fuel feeding means; means for automatically moving the stirrer down into and withdrawing it from the fuel; and means for timing the 30 fuel feeding means to deliver fuel before the commencement of the downward movement of the stirrer.

35 2. In a gas producer the combination of an automatically operated stirrer; automatic fuel feeding means; means for automatically moving the stirrer down into and withdrawing it from the fuel; and means for timing the fuel feeding means to deliver fuel substantially at the beginning of the upward movement of the stirrer.

40 3. In a gas producer the combination of a poker-shaped stirrer; a rocking bearing for the poker mounted on the producer and through which the poker is slidable; automatic means for swinging the poker in the fuel; means for automatically moving the poker down into and withdrawing it from the fuel; automatic fuel feeding means; and means for timing the fuel feeding means to 45 deliver fuel before the commencement of the downward movement of the stirrer.

45 4. In a gas producer the combination of a poker-shaped stirrer; a bearing for the poker mounted with a ball and socket joint on the 50 producer and through which the poker is slidable; automatic means for swinging the poker in a closed curve in the fuel; means for automatically moving the poker down into and withdrawing it from the fuel; automatic fuel feeding means; and means for timing the fuel feeding means to deliver fuel before the commencement of the downward movement of the stirrer.

55 5. In a gas producer the combination of a poker-shaped stirrer; a bearing for the poker

mounted with a ball and socket joint on the producer and through which the poker is slidable; automatic means for swinging the poker in a closed curve in the fuel; means for automatically moving the poker down into 70 and withdrawing it from the fuel.

6. In a gas producer the combination of a poker-shaped stirrer; a bearing for the poker mounted on the producer with a ball and socket joint and through which the poker is 75 slidable; guides carried by the producer; a frame movable on the guides to and from the producer; a spindle journaled in the frame; an arm on the spindle to which the upper end of the poker is loosely secured; means for rotating the spindle and for simultaneously automatically reciprocating the frame on the guides.

7. In a gas producer the combination of a poker-shaped stirrer; a bearing for the poker 85 mounted on the producer with a ball and socket joint and through which the poker is slidable; guides carried by the producer; a frame movable on the guides to and from the producer; a spindle journaled in the frame; 90 an arm on the spindle to which the upper end of the poker is loosely secured; a threaded shaft parallel to the guides and secured to the producer; a gear wheel journaled on the frame and threaded to screw on said shaft; a 95 gear wheel on said spindle; and means for simultaneously rotating said gear wheels.

8. In a gas producer the combination of a poker-shaped stirrer; a bearing for the poker mounted on the producer with a ball and 100 socket joint and through which the poker is slidable; guides carried by the producer; a frame movable on the guides to and from the producer; a spindle journaled in the frame; an arm on the spindle to which the upper end 105 of the poker is loosely secured; a threaded shaft parallel to the guides and secured to the producer; a gear wheel journaled on the frame and threaded to screw on said shaft; a gear wheel on said spindle meshing with the 110 aforesaid gear wheel; a shaft journaled on the producer and slidable through a bearing on the frame; a pinion meshing with one of the aforesaid gear wheels and slidable with a feather key and key-way on the last mentioned 115 shaft.

9. In a gas producer the combination of a poker-shaped stirrer; a bearing for the poker mounted on the producer with a ball and socket joint and through which the poker is 120 slidable; guides carried by the producer; a frame movable on the guides to and from the producer; a spindle journaled in the frame; an arm on the spindle to which the upper end of the poker is loosely secured; a threaded shaft parallel to the guides and secured to the producer; a gear wheel journaled on the frame and threaded to screw on said shaft; a gear wheel on said spindle meshing with the aforesaid gear wheel; a shaft journaled 125 130

on the producer and slideable through a bearing on the frame; a pinion meshing with one of the aforesaid gear wheels and slideable with a feather key and key-way on the last mentioned shaft; a reversible drive for said shaft; and means whereby the frame at predetermined limits of its movement in either direction changes the direction of the drive.

10. In a gas producer the combination of a poker-shaped stirrer; a bearing for the poker mounted on the producer with a ball and socket joint and through which the poker is slideable; guides carried by the producer; a frame movable on the guides to and from the producer; a spindle journaled in the frame; an arm on the spindle to which the upper end of the poker is loosely secured; a threaded shaft parallel to the guides and secured to the producer; a gear wheel journaled on the frame and threaded to screw on said shaft; a gear wheel on said spindle; means for simultaneously rotating said gear wheels; and means whereby the frame at predetermined limits of its movement in either direction 25 changes the direction of the drive.

11. In a gas producer the combination of a feed hopper; a movable closure for its lower end; a movable closure above its lower end; an automatically reciprocated part; means whereby said reciprocating part controls the opening and closing of the lower closure while the upper is closed, and opens and closes the upper closure while the lower is closed.

12. In a gas producer the combination of a feed hopper; a movable closure for its lower end; a movable closure above its lower end; an automatically reciprocated part; a stirrer reciprocated by said part; means whereby said reciprocating part controls the opening and closing of the lower closure while the upper is closed, and opens and closes the upper closure while the lower is closed.

13. In a gas producer the combination of a feed hopper; a gate closure hinged at its lower end; a slide closure adapted to close the hopper above its lower end; an automatically reciprocated part; means whereby said reciprocating part controls the opening and closing of the lower closure while the upper is closed, and opens and closes the upper closure while the lower is closed.

14. In a gas producer the combination of a feed hopper; a gate closure hinged at its lower end; a slide closure adapted to close the hopper above its lower end; an auto-

matically reciprocated part; a stirrer reciprocated by said part; means whereby said reciprocating part controls the opening and closing of the lower closure while the upper 60 is closed, and opens and closes the upper closure while the lower is closed.

15. In a gas producer the combination of a grate carried by the producer and a removable tank independent of the grate forming 65 a water seal for the grate and a receptacle for ashes.

16. In a gas producer the combination of a grate; a tank laterally removable and forming a water seal for the grate and a receptacle 70 for ashes, and having one end adapted to be reduced in height to permit of the receptacle being drawn away from the grate.

17. In a gas producer the combination of a grate; a tank laterally removable and forming 75 a water seal for the grate and a receptacle for ashes, and having one end divided horizontally, the upper part being hinged on the lower so that the end may be reduced in height to permit of the receptacle being 80 drawn away from the grate.

18. In a gas producer the combination of normally inoperative feed mechanism; ash eliminating mechanism; stirring mechanism; means for simultaneously operating 85 the stirring and ash eliminating mechanism; means whereby the stirring mechanism at predetermined times causes the operation of the feeding mechanism.

19. In a gas producer the combination of 90 feed mechanism; ash eliminating mechanism; stirring mechanism; means for simultaneously operating the stirring and ash eliminating mechanism; means whereby the stirring mechanism at predetermined times 95 causes the operation of the feeding mechanism; and means for varying the rate of action of the ash ejecting mechanism.

20. In a gas producer the combination of 100 feed mechanism; ash eliminating mechanism; stirring mechanism; means for simultaneously operating the stirring and ash eliminating mechanism; means whereby the stirring mechanism at predetermined times 105 causes the operation of the feeding mechanism; and means for varying the relative rate of action of the feed and ash eliminating mechanism.
